VENDING MACHINE

Matthew H. Loughridge, Bogota, N. J.

Application February 12, 1931, Serial No. 515,289

27 Claims. (Cl. 225—21)

This invention relates to vending machines which may be coin controlled and some of its objects are to provide a vending machine for articles of food which has to be preserved at a low temperature, to provide a vending machine for delivering a measured quantity of the material. Further objects of the invention include a detachable container for the material. The invention further includes a cooperative action between a plurality of delivery devices, the one being ancillary to the other, sometimes called a two-stage machine, an interlocking arrangement whereby the machine cannot be improperly operated and in which each operation must be completed before another operation can be started. Another object of the invention is to provide a plurality of measuring containers for a liquid controlled by a valve and operative to deliver a measured quantity of the liquid by changing the position of the containers. The invention also resides in the construction and arrangement of the parts whereby the mechanism can be readily cleaned and kept in a sanitary condition.

The invention is described in detail in the following specification and is illustrated in the accompanying drawings, in which,

Fig. 1 is a front elevation of a portion of a vending machine for vending liquids according to this invention; Fig. 2 is a plan view, partly sectioned, showing the operating mechanism used in Fig. 1; Fig. 3 is an enlarged plan view of the measuring containers and locking mechanism; Fig. 4 is an elevation corresponding to Fig. 3 with certain parts of the measuring containers and the valve mechanism shown in section; Fig. 5 is a detail of the toggle mechanism used to rock the measuring containers; Fig. 6 is a horizontal section of the valve mechanism and spigot attachment; Figs. 7 and 8 are details of the valve mechanism for feeding and discharging the measuring containers; Fig. 9 is a sectional front view of the measuring containers in the position reversed to that shown in Fig. 4; Fig. 10 is a detail, partly sectioned, showing the valve parts leading to the measuring containers; Fig. 11 is a plan view of the locking mechanism whereby the operation of the machine is locked and released for operation; Fig. 12 is a side elevation, partly sectioned, corresponding to Fig. 11; Fig. 13 is a transverse elevation, partly sectioned, of the locking mechanism as shown in Fig. 12 and Fig. 14 is a plan view corresponding to Fig. 11, but with the locking mechanism in the reversed position relative to Fig. 11.

Some of the features of this invention apply

to vending machines in general, and other features are specific to a plurality of operating mechanisms, as fully described in the specification.

Machines constructed according to this invention may be used for dispensing liquids, in which a coin releases the mechanism so that in the first operation a cup is delivered and at the same time the measuring containers are released for operation. These containers preferably comprise a pair of cups arranged to rock upon the spigot outlet of the liquid reservoir and are so constructed that when they are rocked in one direction, one of the containers is raised and the other is lowered and this operation of rocking the containers connects the one that is raised with the discharge orifice and connects the one that is lowered with the supply reservoir so that as one cup is being discharged, the other is being refilled. A handle is provided for rocking these containers and its movement is controlled by the locking mechanism in such a way that it can only make one movement for each movement of the locking mechanism, thus maintaining the condition of synchronism between the locking mechanism and the movement of the cup containers. The locking mechanism, as shown in the drawings, has a reciprocating movement which moves it to the right for one operation of the cup containers and moves to the left for the next operation of the cup containers and again moves it to the right for the next operation of the cup containers so that the cups are alternately filled and refilled each time the mechanism is unlocked by a coin.

The invention is shown in connection with dispensing liquids which may be suitably refrigerated or chilled in the storage reservoir.

One application of this invention to liquid dispensing machines will be understood from Figs. 1 and 2 in which 101 is the front of a machine preferably of the type which is mechanically refrigerated and contains an interior reservoir of liquid 104 which is fed from the detachable reservoir 105. The case is preferably heat insulated as indicated at 102 and may contain the brine tank 103 surrounding the liquid receptacle 104. The cup container 106 is preferably mounted in front of the machine with a cup delivery orifice at 107 and also a coin slot mechanism 108 is mounted on front of the machine for receiving the coin to permit the operation and provided with a rotating handle 109 which connects with the crank 117 on the interior and operates the locking mechanism, hereafter to be described,

and also through connection 118 operates the cup dispenser 106 to deliver a cup for each movement of the rod 118. It should be understood that the cup dispenser is a commercial article and it is unnecessary to describe it in detail, at this time. The front of the machine is also provided with a spigot 112 for delivering the liquid, an operating handle 110 for operating the delivery mechanism and a tray 113 for supporting the cup below the spigot.

The liquid dispenser as illustrated in Figs. 3, 4, 6, and 9 will now be described. The receiving tank 104 is provided with an outlet pipe 142, Fig. 6 and to this pipe the stem 122 is clamped by the nut 141 in such a way that the stem may be readily removed and the dispensing mechanism therewith for cleaning purposes and if necessary a removable aperture may be provided at front of the casing 101 as indicated in dotted outline 101a so that this mechanism may be removed and replaced.

Stem 122 constitutes the bearing of the dispenser mechanism, the valves whereby this mechanism is controlled and supports the spigot outlet 112. It will be noted that the inner end of stem 122 is provided with a central passage 143 which terminates in a passage 144. It will also be noted that the outer end of this stem is provided with a central passage 145 which terminates in a transverse passage 146. Mounted upon the stem 122 are the measuring containers 114 and 114a which, as shown, are made of a casting 121 having a central aperture for the stem 122 which entirely encloses the portion of the stem 122 with the transverse apertures or ports and certain passages that register with these ports in certain positions of the measuring or the dispensing device. The casting 121 of the dispensing device is provided with suitable covers, preferably of sheet metal as indicated at 114 and 114a in Fig. 3 so that each end of the dispensing device constitutes a container of like capacity. These sheet metal covers may be made removable for sanitary reasons. An oblique passage, as indicated at 152 in Fig. 4, leads from the bottom of the cup or container 114 to the outlet passage 145, leading to the spigot 112 and, at the same time, another passage 151 registers with the passage 143 leading to the supply pipe 142 as indicated in Fig. 6, so that when the dispensing mechanism is in the position indicated in Fig. 4, the container 114 is connected with the delivery orifice or spigot and container 114a is connected with supply reservoir. Under these conditions the container 114 is emptied and the container 114a is filled.

When the position of the delivery mechanism is changed to correspond with that shown in Fig. 9, the cup or container 114a is raised and the container 114 is lowered and in this position container 114a connects, by passage 153, with the delivery orifice 145, while the container 114 is connected, by passage 154 now in register with the transverse ports 144 leading to the supply pipe 142 which permits the container 114 to be filled and the container 114a to be emptied. It will be noted from Figs. 4, 6, 8, and 9 that the transverse ports in the stem 122 are horizontal and therefore the vertical passages, indicated in Figs. 4 and 9, are closed while the horizontal passages are connected with the passages in the stem 122 and by reversing the position of the container mechanism, the vertical passages are moved to the horizontal position and the horizontal passages are moved to the vertical position. This has the effect of alternately connect-

ing one container to the supply and the other to the delivery spigot, thereby securing the desired operation. It should be observed that the delivery passage, as for instance, 152, Fig. 4 is so located as to drain the entire contents of the container when in the delivery position and, at the same time, the filling passage enters the container at the top and at this time the container is below the level of the supply reservoir. It is possible that in operation a certain amount of air may be trapped in the containers as they are being filled. However, this does not materially influence the operation of the machine, as the air pressure thus stored assists in discharging the contents when the container is brought into the discharging position.

The dispensing apparatus is operated by the handle 110 through the shaft 123 upon which is mounted the T shaped member 125, with the projecting jaw 135 arranged to engage the pin 137 on the lug 138 formed integral with the casting 121. The shaft 123 is pivoted in alignment with the stem 122 so that as it is rotated to move the arm 135 to the right the pin 137 rides in the slot 136 and the spring 139 is compressed until the mechanism passes the center point whereupon the spring expands and completes the rocking movement of the delivery mechanism. This arrangement provides for rocking movement of the delivery mechanism by the exposed handle 110 and the toggle mechanism, including the spring 139 insures a complete movement of the delivery mechanism as it passes the center point.

In order to prevent the operation of the mechanism, except when the apparatus is released, the horizontal bar 125 is provided with a pin 126 in one end and a pin 127 in the opposite end. As the handle 110 is rocked these pins intersect or engage the locking bar 115 and the locking bar prevents the rocking movement of the delivery mechanism, except when it stands in the released position. For this purpose certain slots are provided in the locking bar 115 which register with the pins 126 and 127 so that in the released position these pins can move freely through the slots 45 in the locking bar. This movement can only be made in one direction so that when the delivery mechanism has completed its movement in one direction it cannot be moved back again by the handle 110 until the locking bar has changed its 50 position and brought a new set of slots into register with the pins 126 and 127, thereby releasing the mechanism for an operation in the reverse direction.

In Figs. 3 and 4 it will be noted that the locking bar 115 which slides in the guide plate 116 is provided with a pair of slots 130 and 131 and the slot 130 is provided with a spring latch 132; it is also provided with another pair of slots 128 and 129 and the slot 129 is provided with a spring 60 latch 133 which, by the action of spring 134, is normally arranged to close the slot 129 against downward movement but permits a free upward movement through the slot.

With the locking bar in the position shown in Fig. 4 relative to the arm 125 it will be noted that pin 126 registers through slot 131 and moves freely through this slot, also pin 127 moves upward through slot 130 without obstruction, however, when the pin reaches the top of locking bar the latch 132 is forced under it and it cannot be moved back again, thus as shown in Fig. 12 the locking bar has been moved to the position so that the mechanism may be operated to elevate the container 114 and to lower the container 75

114a and no further movement of the mechanism can be made until the locking bar 115 moves to the right so that slot 128 registers with pin 127 and slot 129 registers with pin 126. In this 5 position it is apparent that the arm 125 may be reversed so as to bring the pin 126 above the latch 133 where the delivery mechanism is again locked with the container 114a elevated and the container 114 lowered. It will thus be noted that by 10 the alternate movement, back and forth, of the locking bar 115, the mechanism is released for a single movement only, corresponding to each movement of the locking bar.

The coin slot mechanism 103 is a commercial 15 article that assumes a variety of forms and may be arranged to operate the mechanism by a rotary motion or by a reciprocating motion either of which may be applied to lock or release the arm 125 for a single movement corresponding to 20 each movement of the coin slot mechanism. In the mechanism shown the coin slot mechanism operates a crank or cam corresponding to 117 through the shaft 109a so as to produce an effective operation of limited character, in one direction only. That is to say, when a coin is inserted in the mechanism and the handle 109 rotated the crank 117 is moved therewith through an idle movement and if for any reason the coin slot mechanism refuses the coin this handle 25 movement cannot be completed and the apparatus fails to unlock. On the other hand when the idle movement is fully completed then the device performs its unlocking function by a spring action which moves it back to the starting position. This spring action on the crank 30 117 is arranged to operate the slide alternately in opposite directions for each operation of the mechanism.

The crank 117 through the link 161 and the 35 rod 162 moves the ratchet head 119 in accordance with the movement of the shaft 109a. In the position shown in Fig. 11 when the ratchet head has made a complete movement it latches at 163 to the head 164 of the lever 165 which is 40 pivoted at 166 in the mechanism frame 167 and the lever 165 by the link 168 and the arm 169 connected at 170 with the lock bar 115 moves this lock bar in the reverse direction and to substantially the same extent as the ratchet head 119 is 45 moved. This positions the locking bar for releasing the delivery mechanism for a single movement. When the locking bar has been thus moved the detent 172 on the top of this bar is moved into the position indicated in Fig. 14. When the 50 ratchet head 119 is again moved towards the right it latches on the detent 172 and moves the locking bar 115 in the reverse direction to which it was previously moved and, at the same time, moves the detent head 164 forward restoring the 55 conditions shown in Figs. 11 and 12 so that the mechanism is now in the original position and upon a third operation of the shaft 109a will move the locking bar to the first position; thus the locking bar is automatically moved back and forth to the unlocking position for each complete movement of the handle 109.

In order to insure the proper latching between the ratchet head and the detents 164 and 172, toggle mechanism is provided which comprises 60 the rotating plate 182 provided with the grooved pins 183 and 184 between which the bar 162 moves. A spring 185 is provided which, in the position shown in Fig. 11 tends to rotate the plate 182 which is mounted on the pivot 181, in a direction 65 to swing the ratchet head 119 to engage the de-

tent 164. As soon as the lever 165 is moved towards the left the bar 188 attached thereto and sliding in the guide 189 engages the arm 190 connected with the plate 182 thereby rotating plate 182 so as to bring the spring 185 beyond the pivot 181 and thereby move the plate into the position shown in Fig. 14 which applies the grooved pins or rollers 183 and 184 to the opposite sides of the bar 162 thus deflecting this bar to the position shown in Fig. 14 which is the latching position to engage the detent 172 on the locking bar 115. When the locking bar 115 is moved towards the left the extension 186 engages the arm 187 on the plate 182 thereby rotating this plate until the pin 183 passes beyond the center and the toggle action of the spring completes the movement of 182 to the position shown in Fig. 11 which restores the bias to the rod 162 in the horizontal direction so that the 10 operation of the mechanism is again reset. The 15 ratchet head 119 is shaped in such a manner that when it is in the latched position it holds this position until the movement is completed.

The purpose of the mechanism described is to alternately release the pair of delivery cups 20 so that they may be alternately brought into the filling and delivery position and it is apparent that the controlling mechanism can be constructed in a variety of forms of which that shown should be taken as diagrammatic.

A two stage refrigerated vending machine of 25 the type in the present application is described in U. S. Patent 1,799,755, April 7, 1931.

Having thus described my invention, I claim:

1. A vending machine comprising a pair of containers, a stem, said containers mounted to rotate on said stem, a supply connected with one end of said stem and a delivery connected with the opposite end of said stem, means for connecting one of said containers with said supply 35 and for connecting the other container with said delivery in one position and means for reversing these connections when said containers are in the reversed position and coin controlled means for changing the position of said containers.

2. A vending machine comprising a pair of containers, a stem connected at one end with a supply and at the opposite end with a delivery orifice, said containers mounted to rotate on said stem so that one has a raised and the other a lowered position, means connecting the container in the raised position with said delivery orifice and connecting the container in the lowered position with said supply and coin controlled means for changing the position of said containers.

3. A vending machine comprising a container, a stem having a supply connected to one end and a delivery orifice connected to the other end, said container being rotatably mounted on said stem, means connecting said container with said supply when rotated in one direction and connecting said container with said delivery orifice when rotated in the opposite direction and coin controlled means for rotating said container.

4. A vending machine comprising a container, a stem having a supply connected to one end and a delivery orifice connected to the other end, said container being rotatably mounted on said stem, means connecting said container with said supply when rotated in one direction and connecting said container with said delivery orifice when rotated in the opposite direction and a toggle mechanism for rotating said container.

5. A vending machine comprising a container, a stem having a supply connected to one end

- and a delivery orifice connected to the other end, said container being rotatably mounted on said stem, means connecting said container with said supply when rotated in one direction and connecting said container with said delivery orifice when rotated in the opposite direction and means for automatically completing the rotation of said container after it is initiated.
6. A vending machine comprising a container, 10 a stem having a supply connected to one end of said stem and a delivery orifice connected to the other end of said stem, said container being rotatably mounted on said stem, means connecting said container with said supply when rotated in one direction and connecting said container with said delivery orifice when rotated in the opposite direction and a coin controlled locking bar restricting the movement of said container.
7. A vending machine as claimed in claim 6 20 in which the locking bar is alternately moved in opposite directions.
8. A vending machine comprising a pair of containers mounted on a frame having a central aperture, a stem in said aperture forming a pivotal mounting for said frame, said stem having an axial conduit connecting with said containers, a spring clamping said frame on said stem, a toggle mechanism for rocking said frame on said stem and coin controlled means 30 for locking said mechanism.
9. A vending machine comprising a pair of containers mounted on a frame having a central aperture, a stem in said aperture forming a pivotal mounting for said frame, said stem having an axial conduit terminating at one end connecting with one of said containers and an independent axial conduit terminating at the other end connecting with the other container, said connections being controlled by the positions 40 of said frame on said stem.
10. A vending machine comprising a pair of containers mounted on a frame having a central aperture, a stem in said aperture forming a pivotal mounting for said frame, said stem having an axial conduit from one end and an independent axial conduit from the opposite end with transverse apertures connecting to said conduits and conduits arranged to connect one of said containers with one of said axial conduits 50 when said frame is in one position and with the other axial conduit when the frame is in the opposite position.
11. In a vending machine, a container, a delivery mechanism having two positions obtained 55 by movement in opposite directions for delivering a measured quantity from said container, a locking bar sliding between two positions and releasing said delivery mechanism for one operation in each position and a coin slot mechanism alternately operating said bar to each position when released by a coin.
12. In a vending machine, the combination of 60 a container, a delivery mechanism having two positions obtained by movement in opposite directions for delivering a measured quantity from said container, a locking bar having two positions and releasing said delivery mechanism for one operation in each position, a cup container, and a coin slot mechanism alternately operating said locking bar to each position and releasing a cup for each operation.
13. In a vending machine, the combination of 65 a container, a delivery mechanism having two positions obtained by movement in opposite directions for delivering a measured quantity from
- said container, a locking bar having two positions and releasing said delivery mechanism for one operation in each position and a coin slot mechanism alternately operating said locking bar to each position.
14. In a dispensing machine, the combination, a lever, a liquid container and a delivery mechanism, a pair of cup containers mounted for rotation connected with said delivery mechanism and 10 container and means whereby the operation of the lever alternately operates said cup containers in opposite directions for the delivery of liquid from the container and a toggle mechanism for completing the rotation of said containers. 15
15. A machine as in claim 14 in which each operation of the lever positions one of said cups for filling and the other cup for delivery of the material therefrom.
16. In a dispensing machine, the combination, 20 a material container, a shaft with a passage therein, a pair of cups mounted to rotate on said shaft, a handle for rotating said cups alternately in opposite directions, a mechanism for restricting the movement of said handle and means for connecting said cups alternately with said passage.
17. In a dispensing machine, the combination, a material container, a pair of cups connected with said container and mounted for rotation, a handle for rotating said cups in opposite directions, 30 a cup container operated to deliver cups and a mechanism operating said cup container to deliver cups and restricting the movement of said handle.
18. A dispensing machine as in claim 17 in 35 which the mechanism operating the cup container is released by a coin slot mechanism.
19. In a dispensing machine, the combination, a locking bar, a container connected with a delivery mechanism, a rotating shaft with a lever 40 thereon for operating said delivery mechanism, locking means on said shaft engaging said locking bar and arranged so that the shaft is released for each operation of said locking bar for a movement, alternately, in opposite directions. 45
20. A liquid dispensing machine comprising a pair of containers, a stem, said containers mounted to rotate on said stem, a liquid supply connected with one end of said stem and a delivery connected with the opposite end of said stem, means 50 for connecting one of said containers with said supply and for connecting the other container with the delivery in one position and means for reversing these connections when said containers are in the reversed position. 55
21. A liquid dispensing machine comprising a pair of containers, a stem connected at one end with a supply and at the opposite end with a delivery orifice, said containers mounted to rotate on said stem so that one has a raised and the other 60 lowered position and means connecting the container in the raised position with said delivery orifice and connecting the container in the lowered position with said supply.
22. A liquid dispensing machine comprising a 65 container, a pair of cups mounted to be raised and lowered and a valve connecting said cups with said container, a housing for said container and cups, means extending through the wall of said housing for raising and lowering said cups and 70 means for operating said valve to fill the cup in the lower position from said container and for delivering the liquid from the cup in the raised position.
23. A liquid dispensing machine comprising a 75

5 container, a pair of cups mounted to be rotated alternately in opposite directions and to alternately connect with said container and with a delivery orifice, means for initiating the movement of said cups for each direction of rotation and means for automatically completing the movement of rotation.

10 24. A liquid dispensing machine comprising a main container, a shaft having a passage connected with said main container, a delivery mechanism having a container and mounted for rotation on said shaft, means connecting said container with said passage when in one position and connecting said container for delivery when in the 15 opposite position and means for rotating said mechanism.

20 25. A liquid dispensing machine comprising a container, a plurality of cups mounted to be raised and lowered, a valve connecting said cups with said container, means for raising and lowering said cups and operating said valve whereby one of said cups is connected with a delivery orifice and another cup is connected with said container

and means for automatically completing the movement of said cups to the raised and lowered positions.

25 26. A liquid dispensing machine comprising a container, a plurality of cups mounted to be raised and lowered, a valve connecting said cups with said container, means for raising and lowering said cups and operating said valve simultaneously whereby the raised cup is connected with a delivery orifice and the lowered cup is connected 10 with the container.

30 27. A liquid dispensing machine comprising a main container, a stem having a passage connected with said main container and another passage connected with a delivery orifice, a delivery container mounted for rotation on said stem, means connecting said delivery container with the passage connected with the main container in one position and means connecting said delivery container with the delivery passage in another 20 position.

MATTHEW H. LOUGHridge.
